CLAIM

The ornamental design for a stand for an optical imaging apparatus, as shown and described.

DESCRIPTION

FIG. 1 is a top, front, right perspective view of a stand for an optical imaging apparatus showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines shown adjacent shaded regions depict boundaries of the stand for an optical imaging apparatus, all other broken lines depict environment of the stand for an optical imaging apparatus, and all broken lines shown form no part of the claimed design.
